UNITED STATES PATENT OFFICE.

SUMTER B. BATTEY, OF NEW YORK, N. Y.

SAFETY-RAZOR AND STROPPING DEVICE.

No. 878,450.

Specification of Letters Patent.

Patented Feb. 4, 1908.

Application filed April 24, 1907. Serial No. 370,036.

To all whom it may concern:

Be it known that I, SUMTER B. BATTEY, a citizen of the United States, and a resident of the city of New York, (borough of Manhattan,) in the county and State of New York, have invented a new and Improved Safety-Razor and Stropping-Device, of which the following is a full, clear, and exact description.

10 This invention relates to safety razors and stropping devices.

The object of the invention is to produce a stropping device of improved construction which can be readily manipulated to strop 15 the blade of a safety razor without injuring the edge thereof.

The device is substantially automatic in its operation with respect to the mechanism which holds the blade and reverses its position on the strop with each reciprocation of the blade.

A further object of the invention is to provide the blade with a guard of improved form to be applied to the razor blade when shaving.

25 The invention concerns itself, further, with the construction of a holder for securing the blade in the stropping device.

The invention consists in the construction and combination of parts to be more fully described hereinafter and particularly set forth in the claims.

Reference is to be had to the accompanying drawings forming a part of this specification, in which similar characters of reference 35 indicate corresponding parts in all the figures.

Figure 1 is a side elevation of the stropping device, a portion of the body thereof being broken away and shown in section; Fig. 2 is 40 an edge elevation of the stropping device, a portion of the same being shown in cross section, while the handle of the device is broken away; Fig. 3 is a vertical section on the line 3—3 of Fig. 1, and upon an enlarged scale; 45 this view illustrates a part of the mechanism for reversing the position of the blade on the return stroke; Fig. 4 is a cross section through the roller and illustrating the manner in which the blade is held therein during the sharpening operation; Fig. 5 is a side elevation showing the razor with the handle and a guard attached thereto for shaving; a portion of the handle is represented in cross section; Fig. 6 is a perspective of the holder for securing the 50 blade in the roller; and Fig. 7 is an end view of the razor as shown in Fig. 5.

Referring more particularly to the parts, and especially to Figs. 1 to 3, 1 represents a circular block or body provided at a suitable point with a radially disposed handle 2 as 60 shown. On the peripheral face of the block 1 near the handle 2, a removable screw 3 is mounted, the purpose of which is to enable the attachment of a razor strop 4 provided with a swivel ring 5 through which the 65 screw passes as indicated. This razor strop is applied like a band around the block, and its opposite end is provided with a shackle 6 of elongated rectangular form, and formed with inwardly projecting gudgeons 7 to 70 which a locking device 8 is pivotally attached. This locking device 8 consists of a plate 9 which is adapted to lie against the side of the block on the side of the shackle adjacent to the handle, and within the 75 shackle it is provided with an outwardly projecting inclined toe 10. This toe is adapted to come against a hook plate 11 which projects outwardly from the face of the block, the outer end of the said hook 80 plate being slightly hooked and projecting toward the handle as shown. In applying this locking or tightening device, it should be understood that the shackle is placed over the hook plate so that the toe 10 engages the 85 face of the hook plate, and the plate 9 is then forced inwardly, so that the extremity of the toe 10 is moved out along the face of the hook plate. In this way the point of engagement between the toe and the hook 90 plate is brought outside of the direction of pull of the shackle, so that the device maintains itself in a locked position.

In order to facilitate the releasing of the device, the edge of the plate 9 adjacent to 95 the handle 2 is preferably slightly bent outwardly, as indicated at 12.

In order to facilitate the application of the razor strop to the block in the manner described, near one face of the block an outwardly projecting circumferential flange or rib 13 is formed, and the edge of the strop is set against this flange, as indicated in Fig. 2. At its center point one face of the block 1 is provided with a pivot pin or bolt 14, the 105 threaded shank of which is received in a threaded sleeve or thimble 15 which is countersunk in the face of the block as shown in Fig. 2. On this pivot bolt there is held loosely a radially disposed arm 16; the outer 110 end of this arm 16 is formed into an enlarged head 17, and this head is disposed just be-

yond the periphery of the block as indicated. In this head there is rotatably mounted a reduced shank 18 of a roller 19, which roller extends transversely across the face of the 5 strop, as will be readily understood. The shank 18 projects beyond the head 17 as shown in Fig. 3, and carries rigidly a pinion 20. This pinion is in mesh with a segment 21 which is pivotally mounted on a suitable 10 pivot pin 22 at an intermediate point on the length of the arm 16. At a suitable point the segment 21 is formed with an outwardly projecting pin 23 which constitutes a handle for operating the device in a manner which 15 will appear more fully hereinafter.

Referring now especially to Figs. 4 to 7: The roller 19 is provided with a longitudinally disposed groove 24 in the side thereof. This groove extends to the end of the roller 20 remote from the shank 18; it is internally enlarged or undercut so as to present the cross section shown in Fig. 4. In this way it may be considered as being formed with a rudimentary bore 25 having a reduced slot 25 formed in the side thereof opening out upon the side face of the roller.

In order to hold the razor blade 26 in the roller, I provide a blade holder 27, the form of which is clearly shown in Fig. 6. This 30 blade holder consists of two oppositely disposed slightly diverging wings 28, of substantially rectangular form, which are integrally united by a longitudinally disposed sleeve or roll 29. This holder is preferably 35 formed of sheet metal and is slightly resilient so that the wings 28 tend to hold themselves in the relation shown in Fig. 6.

Razor blades of a common type used in safety razors are usually provided with 40 transverse openings 30, as indicated in Fig. 4. At suitable points to aline with these openings 30, I provide similar openings 31 in one of the wings 28, and the opposite wing is provided with small pins 32 which project upwardly and which will project into the openings 31 if the wings are forced together.

In placing the razor blade in the roller, the blade is first introduced into the space between the wings 28 with the pins 32 passing 50 through the openings 30 of the razor blade. The wings 28 are then pressed close together, and the holder with the attached blade is then slid longitudinally into the groove 24 from its open end. The form of the groove 55 is such that it will maintain the wings in closed position, so that they clamp the blade securely between them in the manner illustrated in Fig. 4. In order to facilitate the entry of the holder into the groove as suggested, the outer end of the groove is preferably slightly tapered outwardly.

Referring again to Fig. 1, when the razor blade is mounted in the roller as illustrated, it will be evident that if the stropping device 65 is held in the hand and the handle 23 forced

toward the right, the segment 21 will tend to rotate the pinion 20 in a direction which will hold the edge of the razor blade applied to the face of the strop. After the end of this stroke is reached, the operator of the device 70 moves the handle 23 in the opposite direction. The first part of this movement rotates the pinion 20 in the opposite direction, so that the roller 19 turns over and reverses the position of the blade, bringing the edge 75 thereof on the right-hand side of the pinion instead of on the left. The continued movement of the segment toward the left will then carry the razor blade around the periphery of the block, maintaining it in constant contact with the strop, as will be readily understood. In this way the razor blade may be stropped with the greatest facility. The swivel ring 5 facilitates the reversing of 80 the strop, if this is desired.

In order to enable the tension or resistance to the movement of the arm 16 to be adjusted, the pivot bolt 14 is provided with a helical spring 33 which is disposed under the head of the pin and thrusts against the 85 outer face of the arm at the center of the block. By screwing this pivot bolt 14 inwardly, the pressure of the spring upon the arm is, of course, increased, and the resistance to the movement of the arm becomes 90 greater.

The end of the shank 18 is provided with a reduced threaded tip 34, and a handle 35 is adapted to be screwed upon this tip. On account of this arrangement, one is enabled 100 to detach the roller from the arm, whereupon the handle may be attached as indicated in Fig. 5, so that the handle 35, together with the shank 18, constitute a handle for the razor conveniently held while shaving. The 105 razor blade is then provided with a safety guard 36, the construction of which is clearly shown in Figs. 5 and 7. This guard consists of a continuous strap or band 37 which passes around the blade at the outer 110 edge of the holder 27, and is clamped to the holder by means of a small set screw 38, as shown in Fig. 7. This strap 37 is provided with outwardly projecting arms 39 which are slightly inclined as shown, so that their 115 extremities are offset slightly from the edge 40 of the blade, as shown. Between these arms 39 a small pressure roller 41 is pivoted, and this roller is adapted to roll upon the face in advance of the razor blade in shaving. 120 The roller operates to press the flesh in the vicinity of the cutting edge, and prevents the skin from being cut.

While I have described the blade holder with openings 31 and pins 32 disposed opposite to them, it should be understood that the openings and pins are used simply to adapt the holder for use with razor blades of the description illustrated in the drawing; that is, having openings. Where plain ra- 125

zor blades are employed, there is no necessity for the use of the openings 31 or the pins 32, and the blade is held securely in position simply by the clamping action of the wings 5 on the sides of the blade.

Having thus described my invention, I claim as new and desire to secure by Letters Patent:

1. In a stropping device, in combination, 10 a body having a circumferentially disposed face, a strop mounted on said face, and mechanism for applying a razor blade to said strop, and rotating on a fixed axis on said body.

15 2. In a stropping device, in combination, a body having a face disposed in an arc with a strop mounted thereupon, means rotating on the center of said arc for reciprocating a blade applied to said strop, and automatic 20 means for reversing the said blade with each reciprocation.

25 3. In a stropping device, in combination, a body having a circumferentially disposed face, means for attaching a strop upon said face, a pivotally mounted arm, means for mounting a razor blade on said arm in a position to apply the edge thereof to said strop, a handle mounted on said arm for reciprocating the same, and means actuated by said 30 handle for reversing said blade.

35 4. In a stropping device, in combination, a body presenting a circumferentially disposed face, means for attaching a strop upon said face, an arm pivotally attached to said body, means for mounting a razor blade upon said arm in a position to apply the edge thereof to said strop, a member loosely attached to said arm and having a handle adapted to re-

ciprocate said arm, and automatic means for reversing the position of said blade with the 40 reversal of movement of said arm.

5. In a stropping device, in combination, a body having a circumferentially disposed face, means for mounting a strop thereupon, a radially disposed arm attached to said body, 45 a roller rotatably mounted in the end of said arm, a pinion carried by said roller, means for mounting a blade in said roller to apply the edge thereof to said strop, a segment pivotally mounted on said arm and meshing 50 with said pinion, and a handle on said segment affording means for reciprocating said arm.

6. In a stropping device, in combination, 55 a body having a circumferentially disposed face, means for mounting a strop upon said face, an arm pivotally mounted on said body, a roller rotatably mounted at the end of said arm and having a longitudinally disposed groove in the face thereof extending inwardly 60 from the outer end of said roller, a blade-holder adapted to slide into said groove and affording means for clamping a razor blade with its edge near said strop, a member mounted loosely upon said arm and adapted 65 to reciprocate said arm, and means actuated by said loose member for reversing the position of said roller.

In testimony whereof I have signed my name to this specification in the presence of 70 two subscribing witnesses.
